UNITED STATES PATENT OFFICE

JOHN B. SCELZI, OF HOPEWELL, VIRGINIA

DESIGN FOR AN ASH RECEIVER

Application filed April 3, 1930. Serial No. 35,144. Term of patent 7 years.

To all whom it may concern:

Be it known that I, JOHN B. SCELZI, a citizen of the United States, residing at Hopewell, in the county of Prince George and State of Virginia, have invented a new, original, and ornamental Design for an Ash Receiver, of which the following is a specification, reference being had to the accompanying drawing, forming part thereof.

In the drawing:—

Figure 1 is a perspective view of an ash receiver, showing my new design.

Fig. 2 is a top plan view thereof.

I claim:

The ornamental design for an ash receiver as shown.

JOHN B. SCELZI.
